(57) **CLAIM**

The ornamental design for a transport and storage container, as shown.

DESCRIPTION

FIG. 1 is a perspective view showing my new design for a transport and storage container;

FIG. 2 is a front elevational view thereof, with the back elevational view being the same thereto;

FIG. 3 is a top plan view thereof;

FIG. 4 is a bottom plan view thereof; and,

FIG. 5 is a cross-sectional view taken along line 5—5 of FIG. 1.
